Primary Examiner — Marie D. Fast Horse*Assistant Examiner* — Altaira J Swangin(74) *Attorney, Agent, or Firm* — Troutman Pepper Locke LLP; Tim Tingkang Xia, Esq.(57) **CLAIM**

The ornamental design for a “notebook computer” as shown and described.

DESCRIPTION

FIG. 1 is a top, front, and right side axonometric view of a notebook computer, showing my new design;

FIG. 2 is a bottom, rear, and left side axonometric view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash broken lines and any unshaded surfaces in the figures illustrate the portions of the notebook computer that form no part of the claimed design.

1 Claim, 8 Drawing Sheets(56)
